UNITED STATES PATENT OFFICE.

WILLIAM GEORGE WISE, OF NEW YORK, N. Y.

CAN OPENER.

1,413,449.

Specification of Letters Patent. Patented Apr. 18, 1922.

Application filed April 5, 1921. Serial No. 458,715.

To all whom it may concern:

Be it known that I, WILLIAM GEORGE WISE, a subject of the King of Great Britain, residing at New York city, in the county of New York and State of New York, have invented new and useful Improvements in Can Openers, of which the following is a specification.

This invention relates to improvements in can openers and relates particularly to cans containing materials requiring a normally tight seal and which must be frequently opened such as containers for shoe-polish and the like.

One of the objects of the invention is to produce a box or can provided with means for strengthening both sections so as to assure a tight fit of the sections even after the parts have been disassociated and re-associated a large number of times.

Another object is to provide a can which shall be simple of construction, cheap to manufacture, highly efficient for the purpose for which it is designed, and shall present no irregularities to interfere with easy packing or that might be broken or disarranged in shipment.

Another object is to provide a can of this nature with a separable opening member of simple and durable construction which may be readily assembled with a brush so that the brush may be utilized as a lever for effecting opening movements of the member.

Another object is to provide an opening device which shall be simple of construction, and which may be manufactured without the use of expensive dies, and which will not require the expensive assembling operation usual where such openers are secured directly to the can.

With these and other objects in view, which will be more apparent as the specification proceeds, the invention resides in certain novel features of construction and combination and arrangement of parts, the essential features of which are hereinafter fully described, are particularly pointed out in the appended claims, and are illustrated in the accompanying drawing, in which:—

Figure 1 is a side elevation partly in section of a can showing the opener in place ready to effect opening.

Figure 2 is a similar view with the opener turned to effective position.

Figure 3 is an end view of the opening member per se.

Figure 4 is a front elevation of the same. Like characters of reference refer to like parts in all views.

I am aware of the fact that a number of devices have already been invented for the purpose of easily removing the covers of shoe-polish cans and boxes, but in all devices which have come to my attention, a part has been pivotally secured to the can, which part upon being turned has come into contact with a single bead on the can for effecting the desired result. They have all presented structures in which one or more parts have required expensive bending and forming dies, and have required an assembling operation for associating them with the can. They have also been of a more or less delicate character, apt to get out of order or be broken, and have formed objectionable projections on the boxes which interfere with the greatest efficiency in handling and packing. Furthermore they have effected a spreading of the cover flange so that after opening and closing a few times there is no longer that intimacy of contact between the cover and bottom that insures a correct seal, and the paste has been permitted to dry out to such an extent as to render it worthless. The present invention contemplates the providing of a device free from all of these defects and objectionable features.

Referring to the drawing in detail, 10 and 11 represent, respectively, the bottom and top of a can. The bottom section is provided with the usual lateral annular bead 12; and the top section 11 is provided near the top of its flange 13 with a similar lateral annular bead 14. The bead 14 strengthens and stiffens flange 13 and also exerts a tension which tends to force the edge of the flange inwardly if any slight distortion is effected in opening the box, whereby the flange 13 will always remain a snug fit for the bottom.

The opener proper is a tack 15 of elliptical cross-section the minor diameter of which is less than the distance between beads 12 and 14 when the box is closed, and the major diameter of which is equal to or greater than the distance between the said beads when the edges of the box sections are in the same horizontal plane. The tack 15 is provided with a flat rear face from which extend two points or spurs 16 preferably located at opposite ends of the tack head. The pur-

pose of having two spurs is to secure the tack in place and also to prevent its turning when put under strain when in use. The front face of the tack head is curved inwardly at an arc to conform with the curved contour of the side of the box. This tack will be given to the purchaser of the box, and he will affix the tack in the end of his shoe brush 17 where it will always be found when wanted, and where the brush will form a handle for giving the necessary leverage for performing the opening operation.

It will be readily seen that by inserting the tack head 15 between the flanges 12 and 14 of the can and then turning the brush in either direction, the lid will be easily and positively removed from the box or can.

While I have described what I deem to be the most desirable embodiment of my invention, it is obvious that many of the details may be varied without in any way departing from the spirit of my invention, and I therefore do not limit myself to the exact

details of anyth-
vention I
